UNITED STATES PATENT OFFICE.

JACOB JACOBS, OF BROOKLYN, NEW YORK.

DESIGN FOR A TILE.

SPECIFICATION forming part of Design No. 28,084, dated December 21, 1897.

Application filed November 11, 1897. Serial No. 658,212. Term of patent 14 years.

To all whom it may concern:

Be it known that I, JACOB JACOBS, of Brooklyn, in the county of Kings, and in the State of New York, have invented a certain 5 new and original Design for Tiles; and I do hereby declare that the following is a full, clear, and exact description thereof, reference being had to the accompanying drawings, in which—

10 Figure 1 is a perspective view of a tile embodying my invention, and Fig. 2 a plan view thereof.

Letters of like name and kind refer to like parts in each of the figures.

15 The object of my invention is to produce a new and original shape for tiles; and to this end said invention consists in the design for the tile whose leading feature is a square form with flat surfaces at the four corners and 20 scallops or cavities in the sides.

The tile A has an outline that in general

shape has the form of a square, but instead of the corners being right angles they are cut off, forming each a flat or plane surface a . Where each side of the tile adjoins a surface a , there is provided a concavity or scallop a' , and within each side, at its longitudinal center, is an angular indentation or cavity a'' . The surfaces between the scallops and an indentation are plane.

Having thus described my invention, what I claim is—

The design for a tile, substantially as set forth.

In testimony that I claim the foregoing I have hereunto set my hand this 6th day of November, 1897.

JACOB JACOBS.
